UNITED STATES PATENT OFFICE.

EDWIN A. NEWMAN, OF WASHINGTON, DISTRICT OF COLUMBIA, ASSIGNOR
OF ONE-HALF TO DAVID L. SNEDIKER, OF EMPORIA, KANSAS.

DRAWING-BOARD.

SPECIFICATION forming part of Letters Patent No. 408,315, dated August 6, 1889.

Application filed November 28, 1888. Serial No. 292,146. (No model.)

To all whom it may concern:

Be it known that I, EDWIN A. NEWMAN, a citizen of the United States, residing at Washington, in the District of Columbia, have invented certain new and useful Improvements in Drawing-Boards for Draftsmen, of which the following is a specification.

The object of my invention is to provide an improved drawing-board having permanently-attached devices for securing the card-board or drawing-paper in position.

At the present time drawing-paper is usually attached to the drawing-board by means of thumb-tacks. There are many objections to this way of fastening, as it is necessary to adjust the paper every time it is secured to the board in order to obtain a true parallelism between the margins of the paper and the edges of the board. Again, when thumb-tacks are used, the board soon becomes filled with holes, and in a short time it becomes so punctured that the tacks will not stay in position. Another disadvantage is that when the paper is removed it is difficult to replace it in the same position on the board, as is desirable to preserve measurements. Again, the thumb-tacks often obstruct the free movement of the T-square and rule on the drawing-paper.

My invention consists in providing the board with a recess provided with a straight outer edge, against which one edge of the drawing-paper rests, and in securing to the edge or margin of the board outside the recess devices that may be readily manipulated to attach the paper to the board. The securing devices are arranged in recesses in the board and hold the edge or margin of the paper below the general plane of the board, so as to admit of the T-square and other like instruments being used freely on the paper.

My invention also consists in certain details of construction, hereinafter set forth.

In the accompanying drawings, Figure 1 is a plan view of my improved drawing-board. Fig. 2 is a detail view showing particularly a plan view of the securing devices. Fig. 3 is a transverse section through a part of the board on the line 3 3 of Fig. 2, giving a side view of the securing devices. Fig. 4 is a plan view of the two parts of the securing devices

detached from the board, and Fig. 5 is an end view of the same.

The drawing-board A is in most respects of usual well-known construction, the main difference being that on one side it is cut away at a to form a groove having an inclined bottom and terminating in a vertical wall or edge a'. The groove a and vertical wall a' are shown as extending lengthwise of the board; but of course they may be arranged transversely. The edge a' is made straight and true, so as to form a guide for the drawing-paper.

I have shown in the drawings two devices C for securing the paper to the board. These devices are preferably located near each end of the board, as shown, in recesses in the edge of the board outside the recess a.

C indicates a spring-metal finger having at its inner end apertures c for the screws c', which secure it in place, and on the opposite end an enlargement or head b', provided with a small sharp-pointed pin d, projecting downwardly and adapted to pierce the margin of the paper B and secure it to the board, as shown in Fig. 3.

D indicates a catch, preferably formed as shown in Fig. 4, having an enlarged inner end provided with apertures c² for the screws c', which secure it over the edge of the spring-finger C to the board, as shown in Figs. 2 and 3. The outer end of the catch is reduced in size, as shown, and twisted to form a spring-shank f, on the outer end of which is a tooth or nose e, which fits over the end of the finger C when it is depressed and holds it in place. When the finger is depressed and held by the catch, the pin d is firmly held in the paper and board. By taking hold of the catch D at its outer end and bending it sidewise the spring-finger may be lifted and the paper may be removed. The finger C is preferably made of spring metal, so that when the catch is withdrawn it will withdraw the pin d from the paper, and the tooth or nose e of the spring-catch is so formed that it is forced back in the act of depressing the spring-finger C, and then moves forward again as the spring-finger is moved into position upon the card-board.

It will be observed that all the parts of the securing devices are below the plane of the board, so that the T-square and other instruments may be moved across the board without impediment.

The devices are permanently affixed to the board, and are readily manipulated.

Having thus described my invention, what I claim as new, and desire to secure by Letters

10 Patent of the United States, is—

1. The combination, substantially as hereinbefore set forth, of the drawing-board having a recess on one side and the pin-carrying fingers arranged in recesses in the edge of the board.

15 2. The combination, substantially as hereinbefore set forth, of the drawing-board having a recess on one side, the pin-carrying fingers arranged in recesses in the edge of the board, and the catches for holding the fingers in position.

3. The combination, substantially as hereinbefore set forth, of a drawing-board having a recess on one side inclined downwardly toward the edge of the board, a ridge along the margin of the board, the spring-metal pin-carrying fingers arranged in recesses in the edge, and the spring-catches for holding the pin-carrying fingers in position.

25 4. A drawing-board having a recess on one side inclined downwardly toward the edge of the board and devices for securing the edge of the drawing-paper in the recess.

30 In testimony whereof I have hereunto subscribed my name.

EDWIN A. NEWMAN.
